CLAIM

The ornamental design for a kitchen utensil handle, as shown and described.

DESCRIPTION

FIG. 1 is a front perspective view of a kitchen utensil handle of the present invention.

FIG. 2 is a back perspective view of FIG. 1.

FIG. 3 is a front view of FIG. 1.

FIG. 4 is a back view of FIG. 1.

FIG. 5 is a left-side view of FIG. 1, and a right-side view being a mirror image.

FIG. 6 is a top plan view of FIG. 1; and,

FIG. 7 is a bottom plan view of FIG. 1.

The broken lines word shows unclaimed portions of the kitchen utensil handle and forms no part of the claimed design.
